Joseph Nathan

United States Patent Office.

JOSEPH NATHAN, OF WASHINGTON, DISTRICT OF COLUMBIA.

Letters Patent No. 65,259, dated May 28, 1867.

IMPROVEMENT IN BOTTLE-STOPPERS.

The Schedule referred to in these Letters Patent and making part of the same.

TO ALL WHOM IT MAY CONCERN:

Be it known that I, JOSEPH NATHAN, of the city of Washington, in the District of Columbia, have invented a new and useful Improvement in Bottle-Stoppers; and I do hereby declare the following to be a full and correct description of the same, sufficient to enable others skilled in the art to which my invention appertains to understand and use the same, reference being had to the accompanying drawings, which make part of this specification, and in which—

Figure 1 is a longitudinal vertical section of my device in line *x x*, fig. 2.

Figure 2 is a side elevation of the same; and

Figure 3 shows attached parts of the same.

Similar letters of reference indicate corresponding parts in the several figures.

The nature of my invention consists in providing bottles which are to contain soda-water, beer, or any other liquids of effervescent nature, or any liquids which require tight corking, with a stopper which can be withdrawn in a moment without any great exertion, and remain attached to the bottle, and by means of which such liquids can be bottled by one man, which operation now requires at least three.

In the drawing, A may represent the neck of any common soda-water or beer bottle, provided near its mouth with a shoulder, *a*. Around the neck of the bottle, and bearing against the shoulder *a*, is a wire, B, the ends of which are twisted or secured in any well-known manner. On this wire B are fastened two small blocks *b*, provided at their outer side with pins *c* which form the pivots and bearings of the lower ends of the yoke or bow C, which at its top and centre has a circular piece, D, provided with a hole in its centre, into which is cut a female screw-thread. Through this hole passes a screw, E, provided at its top with a thumb-piece, *e*, and at its lower part with a circular piece, *d*, which moves loosely under a metal plate, *f*, to which is secured a circular India-rubber plate, *g*. The screw E need be provided with but a very short screw-thread, only sufficient to give one full turn of the thumb-piece *e* to either withdraw the stopper or tighten it on the bottle. The balance of the shank of the screw E may be made smooth, as shown in fig. 1, so that in uncorking a bottle it is but necessary to turn the thumb-piece *e* once, when the stopper can be lifted straight up from the mouth of the bottle.

Bottle-stoppers now in common use necessitate the use of a cork which is lost when the bottle is opened, as the corks rot by the contact with the fluid in the bottle. By my device the use and loss of corks are obviated, as my stopper always remains attached to the bottle. In bottling effervescent and other liquids, one man fills the bottle, which is then passed over to another man, who inserts the cork, and in turn passes it to a third one, who attaches or secures the wire to hold the cork down. In using my device one man can perform the whole work. After filling the bottle it is only necessary to press down the stopper until the screw-thread touches the piece D, when one turn of the thumb-piece *e* will tightly cork the bottle.

In practice I propose to cast the wire B and blocks *b* in one piece, and spring the yoke or bow into the pins *c*, which will greatly reduce the cost of the manufacture. The device can be made at a less cost than the combined cost of the corks and wires now in use, together with that of the employment of two men, which I dispense with in my device for bottling. I may also place springs between the under side of the yoke or bow C and the top plate of the stopper, which shall lift the stopper as soon as the screw is unscrewed.

Having thus described my invention, what I claim as new therein, and desire to secure by Letters Patent, is—

1. The screw E, the lower part of its shank being made smooth, substantially as and for the purpose described.

2. The blocks *b* on the wire B, constructed and arranged substantially as described.

3. The combination of the wire B, blocks *b*, yoke C, screw E with the lower part of its shank made smooth, and stopper *f g*, substantially as and for the purpose described.

The above specification of my improvement in bottle-stoppers signed this seventh day of May, 1867.

JOSEPH NATHAN.
